UNITED STATES PATENT OFFICE.

W. W. ROBINSON, OF RIPON, WISCONSIN.

IMPROVEMENT IN GATE-CATCHES.

Specification forming part of Letters Patent No. 40,187, dated October 6, 1863.

To all whom it may concern:

Be it known that I, W. W. ROBINSON, of Ripon, in the county of Fond du Lac and State of Wisconsin, have invented certain new and useful Improvements in Gate-Catches; and I do hereby declare that the following is a full, clear, and exact description of the construction and operation of the same, reference being had to the accompanying drawings, in which—

Figure 1 represents a perspective view of the catch and latch, together with sections of the post and gate. Fig. 2 represents a longitudinal vertical section through the catch and latch of the gate. Fig. 3 represents a front view of the catch.

Similar letters of reference where they occur denote like parts in the several figures.

To enable others skilled in the art to make and use my invention, I will proceed to describe its construction and operation.

A represents the gate-post.

B represents part of the gate closing against the post A.

C represents the catches, (their exact shape is represented in Fig. 3,) each being in the shape of a truncated sector of a circle. They are pivoted and hung between the catch-plates *a b* by means of bolts or pins *c*, which pass through the plates *a b* and are secured to the post A. The catches C have free play between the plates *a b*, and said plates are prevented from choking them by a suitable neck on the bolts *c* or by providing the latter with sleeves *d*, which surround the bolts, and on which the catches are hung. The catches C are prevented from dropping beyond a certain point by the projections *g*, which are secured to the plate *a*, and which extend into the spaces *h* of the catches C.

D represents the gate-latch. It is secured

within the part B of the gate and extends sufficiently to be easily grasped and operated. The latch is pivoted at *f* to the gate, and is retained in its position by the action of the spring *p*, which presses against the vertical prong *E*. The part *m* of the latch which comes in contact with the catches has oblique sides, as represented in Fig. 3. When the gate is to be opened, the lever of the latch D is pressed down to the position represented in red lines, Fig. 2, and the part *m* will clear the catches and the gate may be opened. On releasing the latch D the spring *p* will restore it to its first position, and when the gate is closed, the part *m* of the latch D will strike the lower edge, 2, of the catch C, raise the latter to the position represented in red lines in Fig. 3, and strike the curved edge 3 of the opposite catch. The raised catch will then descend by its own weight and both catches will lock the latch effectually between them.

The great advantages of the catches C is that they are very simple in their construction and that they are not liable to get out of order, as they are self-operating and as no spring is required in their operation, which may rust or by hard use may become inoperative.

Having thus fully described the nature of my invention, what I claim herein as new, and desire to secure by Letters Patent, is—

In combination with the double catches C, the spring-latch D, when constructed and operated substantially in the manner and for the purpose set forth.

W. W. ROBINSON.
